VENETIAN BLIND

Charles H. Frankel and Irving M. Sondak, Brooklyn, N. Y., assignors to Frason Company, Inc., a corporation of New York

Application November 13, 1947, Serial No. 785,750

2 Claims. (Cl. 160—178)

1

This invention relates to Venetian blinds.

It is the primary aim and object of the present invention to provide Venetian blinds which are of extremely simple and inexpensive construction, yet of pleasing appearance, and which lend themselves admirably to efficient mass production.

It is another object of the present invention to use colorfast and relatively thin and light plastic sheet material exclusively for the slat-supporting straps, the parts of which may efficiently be joined by the simple expediency of fusing them together.

It is another object of the present invention to provide for ready reinforcement of the plastic slat-supporting straps, to the end that their inherent tendency considerably to sag or expand in hot weather is effectively overcome.

The above and other objects, features and advantages of the present invention will be fully understood from the following description considered in connection with the accompanying illustrative drawings.

In the drawings:

Fig. 1 is a front elevation of a lowered Venetian blind embodying the present invention;

Fig. 2 is a side elevation of the same blind;

Fig. 3 is another front elevation of the blind in raised condition;

Fig. 4 is an enlarged fragmentary section taken on the line 4—4 of Fig. 2;

Figs. 5 and 6 are enlarged fragmentary sections taken on the lines 5—5 and 6—6, respectively, of Fig. 1; and

Fig. 7 is a fragmentary section taken on the line 7—7 of Fig. 5.

Referring to the drawings, and more particularly to Figs. 1 and 2 thereof, the reference numeral 10 designates a Venetian blind which comprises a top casing 12, a bottom rail 14, slat-supporting straps 16 and slats 18. As is customary in blinds of the Venetian type, the top casing 12 is suitably equipped for mounting on a window frame (not shown) and the slat-supporting straps 16 are of the laddered construction shown in Fig. 2. Usually there are two spaced straps 16, each of which comprises opposite suspension bands 20 and a plurality of spaced cross bars or rungs 22 which span the suspension bands 20 and support the slats 18 in the manner shown in Fig. 2. As usual, the suspension bands 20 and cross bars 22 of each strap 16 are made of readily flexible material. The lower ends of the flexible suspension bands 20 of each strap 16 are suitably secured to the bottom rail 14, while the upper ends thereof are suitably secured to a slat-tilting mechanism

2

24 in the top casing 12. This mechanism may assume any conventional form and comprise, for instance, a relatively long roll 26 which is journaled at its opposite ends 28 in suitable bearing brackets 30 in the top casing 12. In order to rock the roll 24 in either direction and accordingly tilt the slats 18, the former may be provided with a worm-gear segment 32 which is in permanent mesh with a worm 34 that may also be journaled in the adjacent bearing bracket 30. Turnable with the worm 34 within the top casing 12 is a pulley 36 over which a cord 38 is passed. The free ends of the depending cord 38 are preferably provided with pulls 40 for convenient manipulation of the cord 38. Thus, on manipulating the cord 38, the slats may be tilted into any desired relative disposition, through intermediation of the gear members 34 and 32, roll 26 and straps 16. The instant Venetian blind may also be raised into the disposition shown in Fig. 3. To this end, there is provided a pull cord 42 which is preferably doubled-back as at 44 and passed at 46 through the overlying slats 18 (Fig. 1) which are to that end apertured at 47 (Figs. 4 and 6). The free ends of the pull cord 42 are suitably secured to the bottom rail 14. The portions 46' of the cord 42 which pass overhead to the slats 18 are guided over pulleys or rolls 48, 50, 52 and 54, that are suitably journaled in the top casing 12. The cord portions 46 passing through the overlying slats 18 are preferably located within the confines of the straps 16, respectively, so as to be hidden from view as much as possible. The suspension bands 20 of the straps 16 and the cords 38 and 42 pass into and from the top casing 12 through suitable openings in the latter (not shown). The Venetian blind so far described is entirely conventional in construction.

The suspension bands 20 and cross bars 22 of each slat-supporting strap 16 are made of any suitable flexible, preferably thin and light, plastic sheet material. The cross bars 22, which are in the present instance made much narrower than the suspension bands 20, are arranged on the suspension bands 20 of each strap 16 in the staggered fashion shown in Fig. 4. The opposite ends or tabs 60 of each cross bar 22 are turned laterally, and preferably upwardly, in the fashion shown in Figs. 2 and 5, and are permanently secured to the adjacent suspension bands 20 by being conveniently fused to the same by the well-known application of heat or a solvent.

The instant suspension bands 20 and cross bars 22 of each strap 16, being made of plastic sheet material which is inherently colorfast,

are likewise colorfast when exposed to artificial or sun light, and may also be made extremely thin so that little space is taken up by the cross bars 22 between the slats 18 when the blind is raised as shown in Fig. 3. In the raised blind, the suspension bands 20 of each strip 16 fold or loop outwardly as at 62 in the same manner in which the suspension bands of the slat-supporting straps of any conventional raised blind fold or loop. Also the plastic straps 16 may readily and conveniently be cleaned directly on the mounted blind by the mere use of a damp rag or soap and water, for instance. The suspension bands 20 and cross bars 22 of each strap 16 may furthermore be left with raw edges and nevertheless have a slightly appearance. This latter factor, coupled with the attachment of the cross bars 22 to the associated suspension bands 20 of each strap 16, make for utmost simplicity in the manufacture of these straps 16 which is naturally favorably reflected in the cost of the blind.

Plastic sheet material suitable for the instant slat-supporting straps 16 has a tendency to expand or elongate noticeably, not so much under load as at varying temperature. Thus, the opposite bands 20 of each strap 16 may show a noticeable difference in their elongation if subjected to different temperatures, as when the sun strikes only those bands 20 which are nearest a window, or when the bands farthest removed from a cold window are subjected to greater heat from a room radiator, for instance. To overcome this single disadvantage, the plastic straps 16, and particularly the suspension bands 20 thereof, are reinforced to prevent their expansion or elongation. To this end, recourse is had to any suitable threads 70 which are substantially inextensible or inexpandable and have considerable tensile strength. Ideal threads for this purpose are nylon threads, for instance. The reinforcement threads 70 extend along and substantially throughout the lengths of the suspension bands 20, respectively, of each strap 16 and are suitably secured thereto, preferably at recurrent spaced intervals so that even a break in one of the threads will have no noticeable adverse effect on the corresponding reinforced band 20. In the present instance, there are attached to each suspension band 20 of a strap 16 two separate threads 70 (Fig. 4) which are aligned with the adjacent end tabs 60 of the two columns of superposed cross bars 22, respectively, and are secured to the band 20 at recurrent spaced intervals by extending through the fused joints between said band and the adjacent end tabs 60 of the cross bars 22 (Fig. 7). The threads 70 run, in the present instance, uninterruptedly along the entire length of each suspension band 20. The threads 70 thus secured to the suspension bands 20 of each strap 16 effectively prevent noticeable longitudinal extension or expansion of the slat-supporting straps 16 even in the hottest weather. Furthermore, the preferred nylon threads have considerable tensile strength which is added to that of the suspension bands 20 of each strap 16. Moreover, the preferred nylon threads are not readily chafed by a slat or slats, should the lat-

ter occasionally come in contact with these threads when the blind is raised as in Fig. 3. Also, breakage of a reinforcement thread 70 anywhere between recurring anchorage points thereof on a suspension band 20 is even less consequential since there are two reinforcement threads 70 placed along each suspension band 20.

While we have shown and described the preferred embodiment of our invention, it will be understood that various changes may be made in the present invention without departing from the underlying idea or principles of the invention within the scope of the appended claims.

Having thus described our invention, what we claim and desire to secure by Letters Patent, is:

1. In a Venetian blind having a plurality of slats and an overhead support, spaced laddered slat-supporting straps suspended from said support, each strap comprising relatively thin spaced flexible plastic suspension bands, flexible slat-supporting rungs of plastic sheeting bridging said bands at recurrent intervals longitudinally thereof and having their opposite ends fused to said bands, respectively, said rungs being of less width than either band and being staggered so as to form spaced columns of superposed rungs longitudinally of said bands, and a pair of substantially inexpandable laterally spaced threads extending externally along and substantially throughout the length of each band and being secured to the latter at recurrent intervals, said threads being disposed between the band and the rung ends fused thereto.

2. In a Venetian blind having a plurality of slats and an overhead support, spaced laddered slat-supporting straps suspended from said support, each strap comprising relatively thin spaced flexible plastic suspension bands, flexible slat-supporting rungs of plastic sheeting bridging said bands at recurrent intervals longitudinally thereof and having their opposite ends fused to said bands, respectively, said rungs being of less width than either band and being staggered so as to form spaced columns of superposed rungs longitudinally of said bands, and a pair of substantially inexpandable laterally spaced nylon threads extending externally along and substantially throughout the length of each band and being secured to the latter at recurrent intervals, said nylon threads being disposed between the band and the rung ends fused thereto.
